UNITED STATES PATENT OFFICE.

DAVID JOHN SCOTT, OF PLAINFIELD, NEW JERSEY, ASSIGNOR TO ISABELLA SCOTT AND DAVID J. SCOTT, EXECUTORS OF WALTER SCOTT, DECEASED.

OFFSET PERFECTING-PRESS.

1,310,506.

Specification of Letters Patent. Patented July 22, 1919.

Application filed September 29, 1916. Serial No. 122,838.

To all whom it may concern:

Be it known that I, DAVID J. SCOTT, a citizen of the United States, and a resident of Plainfield, in the county of Union and State 5 of New Jersey, have invented certain new and useful Improvements in Offset Perfecting-Presses, of which the following is a specification.

The present invention relates generally to 10 offset perfecting presses and has more particularly reference to the arrangement of the units and elements composing such machine.

The main object of the invention is the 15 production of a machine in which both sides of the material will be printed by the offset method in one or more colors, and in which the operating parts are readily accessible for manipulation by the pressman.

Accordingly, the invention consists of the 20 features of construction, combination of parts and arrangement of elements, several preferred forms of which are shown in the accompanying drawings. However, changes may be made in the particular construction 25 herein disclosed without departing from the legitimate and intended scope of the invention.

In the drawings:

Figure 1 is a side elevation, largely in diagrammatic form, of a machine embodying 30 the invention and adapted to print in one color on each side.

Fig. 2 is a horizontal sectional view substantially on the line 2—2 of Fig. 1, also 35 largely in diagrammatic form.

Fig. 3 is a side elevation showing a modified form in which several colors are used.

Similar characters of reference indicate corresponding parts in the different views.

40 Turning first to the exemplification shown in Figs. 1 and 2, the machine consists of a plurality of units, each unit including a form-carrying, a transfer and an impression member. A indicates the form-carrying member of one unit and B the form-carrying member of the other unit. C is the transfer member of one unit and D the transfer member of the other unit. E is the impression member of one unit and F the 45 impression member of the other unit. The form-carrying and transfer members of these units are arranged one above the other and with the impression member out of line with the other members to form an exposed 50 operating side, the two units being grouped 55

with their operating sides outermost so as to render the parts accessible to the pressman. Preferably, each of the transfer members is provided with a throw-off 100 by means of which the said transfer members may be 60 moved outwardly from the operating side and away from the impression and form-carrying members. So also the impression members are provided with throw-offs 101 whereby they may be moved inwardly to- 65 ward each other and away from the transfer members. O indicates the usual inking mechanism and N indicates a dampening mechanism which, if the work requires it, may be used in connection with each form- 70 carrying member.

Suitable web associating and folding mechanisms are employed which are so ar- 75 ranged as to afford unobstructed access to the operating sides of the machine. In the preferred embodiment, here shown, the folder L is located at the side of one of the units but spaced therefrom so as to pro- 80 vide a gangway or platform H. Located above this passageway, in the present em- bodiment, are two angle bars 102 and 103, and located above the units is a slitter 104. It will be observed that by this construction every part of the machine is easily accessible.

I indicates a source of supply of paper in 85 web form preferably located underneath the printing units; and this source preferably consists of two rolls so that while one roll is being perfected another roll may be placed in position ready for use. These rolls of 90 paper are journaled in open sockets I'. The paper is led from one of these rolls over a guide X' and between the impression and transfer members of the first printing couple, thence to the under side of the im- 95 pression member of the second printing couple and between the impression member and transfer member of the second couple; after which the paper passes to a cylinder 104 that divides it into two sections, one of 100 which passes straight to folder L, over guides X' and X², and the other section is passed around angle bars 102 and 103 so as to give the paper two quarter turns and bring it in superposed relation to folder L. 105

To prevent the printed side of the paper from smutting the surface of the impression member of the second unit, an anti-smutting device 37 is arranged in contact with the surface of the impression member of the 110

second unit and is located above it. The dampening mechanisms N and the anti-smutting device 37 may be thrown off by means of levers 105. In the present instance, the 5 dampening mechanism is located adjacent to the operating sides of the machine.

Arranged adjacent to the end of the units is a motor 106 which drives gear 107, that 10 imparts motion to the cylinders comprising the units and which, by means of bevel gears 108, shaft 109 and gearing 110, transmit power to folder L. The transmission gearing described is preferably located below the floor or below platforms, such as 111, located 15 at the ends of the units.

In Fig. 3, the construction of each unit is exactly the same but here an additional unit is provided located beneath one of the other two units with its operating side outermost. 20 The members of this third unit are described as follows: the form-carrying member is indicated by B', the transfer member by D' and the impression member by F'. The relation of the associating and folding devices 25 with respect to the printing units is exactly the same as before. The lead of the web is here from source of supply I that is located below one of the two units that are arranged with their operating sides outermost, up 30 ward between the impression and transfer members of the first unit, then downward to the lower side of the impression member of the lower unit, thence upward between the impression and transfer members of the 35 other of the two first-mentioned units. It will thus be observed that there is a complete unit for each color and that associated with each of the impression members of the two units that print on the second side of the 40 paper is provided an anti-smutting device 37 and 37'.

What is claimed is:

1. A rotary offset web perfecting machine comprising: a plurality of units printing 45 from positive forms on opposite sides of impression receiving material, each unit including a form-carrying, a transfer and an impression cylinder all of substantially the same diameter, the form-carrying and transfer cylinders being arranged one above the other and the impression cylinder out of line with the other cylinders to form an exposed operating side, the units being grouped with their operating sides outermost, and web associating and folding means located to afford 50 unobstructed access to the operating side of the units, said means including a folder, and means for slitting the printed web and for leading the slitted sections in superposed relation to the folder.

2. A rotary offset web perfecting machine comprising: a plurality of units printing 55 from positive forms on opposite sides of impression receiving material, each unit including a form-carrying, a transfer and an im-

pression cylinder all of substantially the same diameter, the form-carrying and transfer cylinders being arranged one above the other and the impression cylinder out of line with the other cylinders to form an exposed 70 operating side, the units being grouped with their operating sides outermost, a folder located at the side of one of the units and spaced therefrom to provide a gangway, and means for slitting and superposing the slitted sections and for leading them to the folder in superposed relation and located to afford unobstructed access to that operating side of the unit to which the folder is adjacent.

3. A rotary offset web perfecting machine comprising: a plurality of units printing from positive forms on opposite sides of impression receiving material, each unit including a form-carrying, a transfer and an impression cylinder all of substantially the same diameter, the form-carrying and transfer cylinders being arranged one above the other and the impression cylinder out of line with the other cylinders to form an 80 exposed operating side, the units being grouped with their operating sides outermost, a folder located at the side of one of the units and spaced therefrom to provide a gangway, means for slitting the web coming from the units, and angle bars located 85 above the gangway between the folder and that unit to which it is adjacent for superposing the slitted product and leading it to the folder.

4. A rotary offset web perfecting machine comprising: a plurality of units printing from positive forms on opposite sides of impression receiving material, each unit including a form-carrying, a transfer and an impression cylinder all of substantially the same diameter, the form-carrying and transfer cylinders being arranged one above the other and the impression cylinder out of line with the other cylinder to form an 90 exposed operating side, the units being grouped with their operating sides outermost, a folder located at the side of one of the units and spaced therefrom to provide a gangway, means for slitting the web and 95 for running one of the slitted sections straight to the folder, and angle bars giving two quarter turns to the other slitted sections to bring the two sections in superposed relation to the folder.

5. A multi-color offset web perfecting machine comprising: a plurality of units printing from positive forms on opposite sides of impression receiving material, each unit including a form-carrying, a transfer 100 and an impression cylinder all of substantially the same diameter, the form-carrying and transfer cylinders being arranged one above the other and the impression cylinder 105 out of line with the other cylinders to form 110

an exposed operating side, two of said units being grouped with their operating sides outermost and a third unit being grouped beneath one of the two units with its operating side outermost, a web supply located under the other of the two first-mentioned units, means for guiding the web through the machine from one unit to the other, and delivery mechanism associated with said unit and located to afford unobstructed access to the operating sides of the units.

6. A multi-color offset web perfecting machine comprising: a plurality of units printing from positive forms on opposite sides of impression receiving material, each unit including a form-carrying, a transfer and an impression cylinder all of substantially the same diameter, the form-carrying and transfer cylinders being arranged one above the other and the impression cylinder out of line with the other cylinders to form an exposed operating side, two of said units being grouped with their operating sides outermost and a third unit being grouped beneath one of the two units with its operating side outermost, a web supply located under the other of the two first-mentioned units, means for leading the web from the source of supply directly above it, thence downwardly to the lowermost unit, and thence upwardly to the unit above it, and delivery mechanism associated with said unit and located to afford unobstructed access to the operating sides of the units.

35 7. A multi-color offset web perfecting machine comprising: a plurality of units printing from positive forms on opposite sides of impression receiving material, each unit including a form-carrying, a transfer and an impression cylinder all of substantially the same diameter, the form-carrying and transfer cylinders being arranged one above the other and the impression cylinder out of line with the other cylinders to form an exposed operating side, two of said units being grouped with their operating sides outermost and a third unit being grouped beneath one of the two units with its operating side outermost, a web supply located under the other of the two first-mentioned units, means for leading the web from the source of supply directly above it, thence downwardly to the lowermost unit, and thence upwardly to the unit above it, an anti-smutting device engaging with the surface of the impression cylinder of the second unit and located adjacent to the upper side thereof, and delivery mechanism associated with said unit and located to afford unobstructed access to the operating sides of the units.

8. A rotary offset multi-color machine comprising: a plurality of units printing from positive forms, each unit including a form-carrying, a transfer and an impression

cylinder all of substantially the same diameter, the form-carrying and transfer cylinders being arranged one above the other and the impression cylinders out of line with the other cylinders to form an exposed 70 operating side, the units being grouped one above the other with their operating sides outermost and facing the same way, and delivery means associated with said units located to afford unobstructed access to the operating 75 sides of the units.

9. A rotary offset multi-color perfecting machine comprising: a plurality of units printing from positive forms, each unit including a form-carrying, a transfer and an 80 impression cylinder all of substantially the same diameter, the form-carrying and transfer cylinders being arranged one above the other and the impression cylinder out of line with the other cylinders to form an exposed 85 operating side, the units being arranged in two sets, one set including one of said units printing one side of impression receiving material and the other set including a plurality of units printing the other side of impression receiving material in several colors one unit of said second set for each color, the units of the second set being grouped one above the other with their operating sides facing the same way, and said sets being grouped back to back with the operating sides of the units outermost.

10. A rotary offset multi-color perfecting machine comprising: a plurality of units printing from positive forms, each unit including a form-carrying, a transfer and an impression cylinder all of substantially the same diameter, the form-carrying and transfer cylinders being arranged one above the other and the impression cylinder out of 100 line with the other cylinders to form an exposed operating side, the units being arranged in two sets, one set including one of said units printing one side of impression receiving material and the other set including a plurality of units printing the other side of impression receiving material in several colors one unit of said second set for each color, the units of the second set being grouped one above the other with their operating sides facing the same way, and said sets being grouped back to back with the operating sides of the units outermost, a source of supply of impression receiving material located beneath the unit of the first 105 set, and delivery mechanism located to afford unobstructed access to the operating side of the units of the second set and spaced therefrom by a gangway.

11. A rotary offset web perfecting machine comprising: a plurality of units printing from positive forms on opposite sides of impression receiving material, each unit including a form-carrying, a transfer and an impression cylinder all of substantially 115 120 125 130

the same diameter, the form-carrying and transfer cylinders being arranged one above the other and the impression cylinder out of line with the other cylinders to form an exposed operating side, the units being grouped with their operating sides outermost, a web supply beneath the units, means for leading the web to the impression cylinder of one unit and thence to the impression cylinder of the other unit, and web associating and folding means located to afford unobstructed access to the operating side of

the units, said means including a folder, and means for slitting the printed web and for leading the slitted sections in superposed relation to the folder. 15

Signed at Plainfield, in the county of Union and State of New Jersey, this 27th day of September, A. D. 1916.

DAVID JOHN SCOTT.
